UNITED STATES PATENT OFFICE.

MICHAEL KENNEDY, OF TROY, NEW YORK.

AUTOMATIC CAR-COUPLING.

SPECIFICATION forming part of Letters Patent No. 285,906, dated October 2, 1883.

Application filed March 5, 1883. (No model.)

To all whom it may concern:

Be it known that I, MICHAEL KENNEDY, of the city of Troy, county of Rensselaer, and State of New York, have invented a new and useful Improvement in Automatic Car-Couplings, of which the following is a specification.

My invention relates to mechanism for actuating the ordinary pin and link used to connect cars; and the object of my invention and improvement is to actuate them to connect automatically and to operate them to disconnect without necessitating the passage between the cars of the person operating them.

My invention consists, as will hereinafter be more fully described, in the combination, with the draw-head of the car, of a vertical latch-pin and connected offset coupling-pin carrier, by which, as the latch-pin is moved upwardly, the coupling-pin is also moved upwardly from 15 out of and so as to disconnect the coupler-link, a horizontal sliding latch-plate arranged to work in a guideway in the draw-head, and being slotted for the passage of the latch-pin, and constructed with a vertical guideway for the 20 coupler-pin, a spring attached to said latch-plate, which forces the slotted edge of the latter to engage with a notch in the vertical latch-pin when the latter is raised, to hold it and the coupling-pin carrier and the coupling-pin 25 30 35 40 45 50 55 60 65 70 75 80 85 90 95 100

up, and a vertical front end to the latch-plate constructed to engage with the end of the entering link, and by which the latch-plate is forced back against the spring to release the latch-pin carrier and coupler-pin, so that they will fall by gravity and the coupler-pin enter the link to hold the latter and connect the cars.

My invention also consists, as will hereinafter be described, in the connected levers, as 40 45 50 55 60 65 70 75 80 85 90 95 100

constructed and arranged upon the car ends, to be operated from the top and end of the car to raise the coupling-pin carrier and coupling-pin, so as to disconnect the cars.

Accompanying this specification, and forming a part of it, there are three plates of drawings, containing five figures, illustrating my invention and the parts of a car with which my invention connects, and in all of which the same designation of parts by letter reference 45 50 55 60 65 70 75 80 85 90 95 100

Figure 1 represents a longitudinal vertical section taken centrally through the mechanism and the parts of a car with which the latter connects, with the latch-pin and coupling-pin carrier shown as raised and the car disconnected. Fig. 2 represents the same illustration of parts shown at Fig. 1, with the pin and link connected. Fig. 3 illustrates in perspective the under side of the car as turned toward the right and the mechanism there attached to operate the latch-pin and connected coupling-pin carrier. Fig. 4 shows an end view of the car in perspective and a connected means for operating the coupler mechanism from the top of the car and side at the end. Fig. 5 represents in perspective the sliding latch-plate, shown as removed from the draw-head.

All the parts of the coupler mechanism are shown as exaggerated in size when compared with the parts of a car with which they connect, to better illustrate them.

The several parts of the apparatus constituting my invention and the parts of a car with which the former connect are designated by letter reference, and their operation is explained as follows:

The letter C indicates the end of the car, and C² its under side, near the end.

D designates the draw-head, and D² its hooded abutting end, with the hood shown as constructed to taper inwardly and upwardly from the outer edge of the bottom, as indicated at d'.

The letter E designates the coupler-pin carrier, which is formed as an offset on and connected with the latch-pin F, so as to move with the latter; and G indicates the coupler-pin.

The letter H designates the sliding latch-plate, which has an opening, I, slightly slotted longitudinally for the passage of the latch-pin, and has constructed in it, as indicated at J, a guideway for the coupler-pin G.

The letters a a designate openings in the top of the draw-head, for the passage of the latch-pin F and the coupler-pin G.

The letter S indicates a leaf-spring, which at its lower end is attached to the sliding latch-plate, as designated at S², and at its upper end, at S³, to the draw-head D.

At *e* there is shown a guideway formed in the draw-head, for the horizontal passage of the latch-plate when moved backward as against or forward by the elasticity of the 5 spring *S*.

The letter *N* indicates a notch made in the vertical side of the latch-pin *F*, adapted to engage with the edge of the opening *I*, made in the sliding latch-plate *H*, when the latter is open to the notch and the pin and coupling-pin carrier are raised to disconnect the pin and link.

The letter *K* designates a vertical end tripping plate made on the sliding latch-plate, with 15 which the end of the entering link *L* is forced to engage as the cars come together, the link being guided to such engagement by the inwardly-tapering bottom of the hood *D*² on the draw-head *D*. When the entering link thus 20 comes in contact with the tripping plate *K*, attached to the sliding latch-plate *H*, it forces the latter back against the force of the spring *S*, and so releases the latch-pin, when it and the connected coupling-pin carrier and coupling-pin descend by gravity, the coupling-pin 25 *G* falling within the link *L* to make the connection between the cars. When the connection is thus made, the coupling-pin carrier rests on the top of the draw-head, and when 30 the link and pin are disconnected the carrier is raised above the draw-head, the last-named position of the parts being indicated at Fig. 2, and the former as shown at Fig. 1.

As thus constructed and arranged, in combination with the draw-head and draw-head hood, the latch-pin, connected coupling-pin carrier, the sliding latch-plate as constructed with the spring, and vertical tripping-plate, as a sub-combination of parts, perform a specific office, due to their construction and arrangement—that of operating the pin and link to connect automatically.

To disconnect the link and pin thus connected, and with the mechanism employed to do it 45 operated from the side of the car, the shaft *T* is constructed with bearings for it to journal in, formed in the hangers *t t* upon the under side of the car, near its edge. The outer ends of this shaft are supplied with the weighted 50 crank-arms *U U*, and at the center of shaft the projecting arm *W*. Upon the hanger *O'*, at *O*², there is centrally pivoted the lever *M*. The arm *W* on the shaft *T* makes a cam engagement with the adjacent end of the lever 55 *M* on its upper surface, as indicated at *m*², so as to force it down and the opposite weighted end of this lever *m*' upwardly, causing the latter to rise and strike the lower end of the latch-pin, and thus force it and the connected coupling-pin carrier upwardly, and also the coupling-pin, and thus disconnect the latter and the link.

To operate the coupler mechanism from the top of the car, so as to disconnect the link 65 and pin, the vertical bar *B*, constructed with

the foot *F*², is used, and arranged so that it can be moved up and down on the end face of the car in guideways, as indicated at *b*³ *b*³. The foot *F*² is bifurcated at the front to pass the latch-pin on each side of the latter, and 70 placed so as to be beneath the edge of the coupling-pin carrier, so that when from the top of the car the bar *B* is pulled upwardly the foot *F*² engages with the under side of the coupling-pin carrier to raise it, the latch-pin, 75 and coupling-pin, and thus disconnect the latter and the link. As shown at Fig. 4, the foot *F*² and bar *B* are shown as down and the latch-pin, coupling-pin carrier, and coupling-pin as raised, to better illustrate the form of 80 the parts.

To operate the bar *B* from the end and side of the car end, the horizontal levers *L*³ *L*³—which are pivoted to the car end at *O*⁴ and to the bar *B* by a slotted opening and pivot, 85 *O*³—are, by means of their end handles, *h h*, pulled down to the position indicated by the dotted line *l l*, which raises the bar *B* and foot *F*² to disconnect the pin and link in the same manner as when the bar *B* is pulled upwardly from the top. At *n n* the horizontal levers *L*³ are oppositely jogged to make the slotted connection with the bar *B* indicated at *O*³. The bar *B*, as thus constructed and applied, 90 can be operated to disconnect the link and pin, 95 in connection with the coupling-pin carrier, from the top and side of the car end.

When the cranks *U U* are drawn down by their weighted arm ends, they are kept in place by the crank-rests *i i*. The end of the pivoted lever *M*, which is weighted at *m'*, also drops down when the actuating shaft-arm *W* ceases to engage with the upper surface of the opposite end of this lever. Weighting the 105 end of this lever *M* at *m'* serves a double purpose, in causing the weighted end to fall away from the pin when not in use, and when impelled upward to strike or tap the end of the latch-pin with a hammer impetus, to free it from any tendency to stick before pressing it 110 upwardly.

Having thus described my invention, what I claim, and desire to secure by Letters Patent, is—

1. In a car-coupler, the combination of a draw-head and draw-head hood, a vertical latch-pin constructed with a latch-notch in its side, a coupling-pin with a connected carrier moving with said latch-pin, openings in the draw-head for the passage of said latch-pin and the coupling-pin, a sliding latch-plate arranged within the draw-head, said latch-plate being constructed with an opening adapted for the passage of said latch-pin and to engage and latch into the notch in the latch-pin, 120 and also constructed with a guideway for the passage of the coupling-pin, a vertical tripping-plate on the end of said latch-plate opposite the link-opening in the draw-head hood, and a spring connecting said latch-plate with the 125 130

draw-head, as and for the purposes herein shown and described.

2. In a car-coupling mechanism, the combination of the coupler-pin carrier E, latch F, latch-plate H, coupler-pin G, spring S, crank-arms U U, shaft T, lever M, and arm W, arranged and constructed to operate as herein shown and described.

Signed at the city of Troy this 28th day of February, 1883.

MICHAEL KENNEDY.
